UNITED STATES PATENT OFFICE.

CHARLES EDGAR MAYNARD, OF NORTHAMPTON, MASSACHUSETTS, ASSIGNOR TO THE FISK RUBBER COMPANY, OF CHICOPEE FALLS, MASSACHUSETTS, A CORPORATION OF MASSACHUSETTS.

TUBE-STRIPPING MACHINE.

1,402,171.

Specification of Letters Patent.

Patented Jan. 3, 1922.

Application filed June 6, 1921. Serial No. 475,220.

To all whom it may concern:

Be it known that I, CHARLES EDGAR MAYNARD, a citizen of the United States of America, residing at Northampton, in the 5 county of Hampshire and State of Massachusetts, have invented certain new and useful Improvements in a Tube-Stripping Machine, of which the following is a specification.

10 My invention relates to a machine and process for stripping rubber tubes from tube forming mandrels; more especially to the stripping of vulcanized rubber inner tubes, used as air containers for pneumatic tire 15 casings, from circular mandrels.

The object of my invention is to provide a faster, cheaper and more satisfactory method of stripping tubes from circular mandrels than has heretofore been employed.

20 My invention will now be explained with reference to the accompanying drawings; in which,

Fig. 1 shows a side view of my machine; 25 Fig. 2 shows a front view, partly in section, of my machine with a mandrel in place ready for the tube to be stripped;

30 Fig. 3 is a plan view of an air ring through which I introduce air pressure underneath a turned back portion of a tube on a mandrel;

Fig. 4 shows a plan view of my machine and driving means with the air-ring detached;

35 Fig. 5 shows a plan view of the connection by which the mandrel is coupled to the means for rotating it, taken on plane Y Y of Fig. 2;

Fig. 6 is a front view of Fig. 5 on plane 40 X X of Fig. 2;

Figs. 7, 8, 9, and 10 are diagrammatic views showing four stages in the stripping of a rubber tube from a circular mandrel.

45 My invention will be more clearly explained by taking three different elements; the driving mechanism, the mechanism for holding and allowing a mandrel to rotate, and the mechanism for supplying the air used for blowing the tube; and then showing how these three operate in combination to accomplish my purpose.

I employ a small motor 10 as a prime mover and transmit power to a shaft 12 through a gear box 14. Splined to the shaft 55 12 is the male portion 16 of a friction clutch

operating with a female clutch portion 18 which is keyed to a shaft 20; a brake drum 19, on the shaft 20, acts in conjunction with a friction brake arm 22, which is pivoted at 24 to a bracket 26.

60

The clutch and brake mechanisms are controlled by a pedal 28 located at an end of an arm 30 which is hinged to the main frame 32 at 34. Pivoted to the arm 30 are two rods 36 and 38. Rod 36 has its upper end 65 40 pivoted to the brake arm 22 and upon upward motion of the arm 30 actuates the brake arm 22 against the brake drum 19. Upon upward motion of arm 30, the rod 38, having on one side the rack 42, actuates a 70 gear 44. The gear 44 meshes with a rack 46 slidable in bearings 48. A bifurcated element 50 extending partially around the groove 52 of the male clutch element 16 is fixed to the rack 46 at 54. Gear 44, through 75 the rack 46 and the bifurcated arm 50 actuates the male clutch portion 16 longitudinally on the shaft 12.

During the cycle of operations of my machine it is desirable that the clutch and brake 80 mechanisms be held in the three following positions relative to one another; clutch out and brake off, clutch in and brake off, and clutch out and brake on. These three positions are easily determined by the operator 85 by pressing down the foot pedal 28 until a pawl 58 on the arm 30 engages with the proper notch on a bracket 60 (relative to the above named positions as shown by the notches 54, 52 and 56). The operator governs 90 the pawl 58 by means of the foot pedal 63, connected to the pawl by the rod 61.

A gear 62, keyed to the shaft 20, meshes with a gear 64 which is keyed to a shaft 66. The shaft 66 is supported by a bearing 68 95 and has a reduced threaded portion 70 at its forward end. A sleeve 72 having a flange 73 and a circular groove 75 is splined at 77 to the shaft 66. Upon the sleeve 72 is an arm 74 having a pin receiving end 76 100 through which a pin 78 may be inserted. A hand wheel 80 is rigidly connected to a nut 82 which engages with the threaded portion 70. A key 84, which is easily removable and engages in any of the longitudinal slots 86 105 on the shaft 66 as well as in the slot 88 of the nut 82, holds the wheel 80 in any desired adjusted position on the threaded portion 70. A plurality of arms 90, rigidly fixed to the wheel 80, have flanges 91 engaging in the 110

circular groove 75. From the foregoing description it is easily seen that the arm 74 may be adjusted as desired along the shaft 66 by the hand wheel 80.

5 The mandrels 92 which I employ are of the circular type and have a circumferential gap 94 in order to allow the rubber tube 96 to be conveniently placed upon and taken off the mandrel. The mandrel has a trans-
10 verse air tight wall 98 at one end which prevents compressed air, which is used for purposes to be described later, from escaping around the inside of the mandrel. At the other end of the opening is a lug 100
15 having a hole therein to receive the pin 78.

I rotatably support the mandrel 92 upon which a rubber tube 96 is mounted, by a plurality of rollers 102. The rollers rotate about pins 104 which are supported by
20 bearings 106 and which are rigidly bolted, as shown by 108, to the main frame. The different sizes of mandrels employed in vulcanizing tubes have a uniform inner circumference 110, but varying outer circum-
25 ferences 112. For this reason the pins acting as bearing for the rollers 102, which are in contact with the outer circumference 112, are adjustable along the slots 114 in the main frame 32 in order to accommodate dif-
30 ferent sized mandrels.

As a means for holding a turned back end of the rubber tube and a means for introducing air pressure underneath that turned back portion, I employ an air-ring 116
35 hinged at 118 with respect to the main frame 32 by means of the bracket 120 in order to allow it to be swung up out of its normal position into a position shown in dotted lines on Fig. 1. The inside diameter of
40 the air-ring is of such size as to allow a mandrel, upon which a tube is mounted, to pass unobstructed through the ring and still cut down all unnecessary clearance. The outside face 122 of the air-ring is beveled
45 to receive a rubber tube end 124 which is turned back and held in position over the outside of the air-ring by a ring 126 beveled on its inside. A plurality of air ports 128 conduct compressed air from any convenient outside source to the pocket 130 formed by the turned back tube.

A circular flexible hoop 132 angular in cross-section, which I will term a sealing ring, has one side 134 attached to the air-ring while the other side 136 fits snugly around the tube 96 which is mounted upon the mandrel. The purpose of the hoop is to prevent any leakage of air between the air-ring and the rubber tube on the mandrel when air is supplied under pressure to the pocket 130. A flange 138 (Fig. 1) on the upper part of the air-ring cooperates with a latch 140, pivoted to the main frame at 142, to hold the air-ring up out of normal position when required.

The procedure in stripping a tube from a circular mandrel is as follows: The mandrel 92, upon which a rubber tube 96 is mounted, is placed in position on the rollers 102 as shown in Fig. 2; the foot pedal 28
70 has its pawl 58 in position 54, in order that the arm 74 may be easily swung around in position by hand to insert pin 78 through a pin receiving hole in the lug 100. The rubber tube is turned back at 124 by hand
75 over the outside beveled portion 122 of the air-ring 116, and the ring 126 is clamped over the outside beveled portion of the air-ring so that the edge of the rubber is held firmly between the two beveled surfaces.
80

The clutch 16 is now thrown in by engaging the pawl 58 in position 52. The arm 74 is mechanically rotated by the previously described mechanism and rotates the mandrel 92 upon the rollers 102. As
85 the mandrel rotates, air pressure is introduced from any convenient outside source through the air ports 128 and into the pocket 130 formed by the turned back portion of the tube. Since the rubber tube is gripped
90 at 124 to the non-rotatable air-ring, the tube will be stripped back upon itself as the mandrel is rotated, the air pressure in the pocket formed by the turned back portion of the tube acting as a lubricant. Figs. 7,
95 8, 9, and 10, show four positions of the rubber tube as it is being stripped from the mandrel. The arm 74 is rotated until it assumes the positions shown by Fig. 9. By this rotation of the arm the tube 96 is stripped back to the point 138. The machine is then stopped by pressing the foot lever 28 until pawl 58 engages in the notch 56. At this position the clutch is disengaged and the brake arm 22 is bearing
100 against the brake drum 19, thereby holding the arm 74 and therefore the mandrel 92 from turning. As the arm 74 terminates its rotation in the position as shown by Fig.
105 9, the air-ring is in a position in the circumferential gap 94. The outside ring 126 is then removed, thereby releasing the end of the rubber tube, and the air-ring 116 is turned up out of the way as shown in Fig. 10.
110

115 After a tube has been about half stripped from a mandrel it is pulled off by hand over the remaining portion of the mandrel. When the air-ring 116 has been swung up out of the way the end 142 of the rubber tube 96 extending over the gap 94 is gathered together by hand and air under pressure is introduced inside the tube as by inserting a pipe 144 within the end of the tube and gathering the tube about it. As
120 125 the pressure is applied inside the tube, the tube is pulled off the mandrel by the operator. The mandrel is now taken from the rollers and a new mandrel is put in its place ready to have a tube stripped.
130

From the foregoing description it is evident that the complete stripping operation can be accomplished by one man. The operation is fast and gives a transversely uniform pull on the tube as it is being pulled back. The machine is adapted to strip different sized mandrels and is very satisfactory in operation.

Having thus described my invention, I 10 claim:

1. In a tube stripping machine, means for supporting a circular mandrel; means for holding a turned back portion of a rubber tube mounted upon the mandrel; and means 15 for causing a relative motion between the mandrel and the said holding means.
2. In a tube stripping machine, a frame, a plurality of rollers supported by the frame and adapted to rotatably support a circular 20 mandrel; means for rotating the circular mandrel; means for holding a turned back portion of a rubber tube which is mounted upon the mandrel; means for forming a pocket between the portion of the tube 25 turned back and a portion of the tube on the mandrel and means for supplying a fluid under pressure to the pocket.
3. In a rubber tube stripping machine, means for holding a turned back portion of 30 a rubber tube which is mounted upon a mandrel; means for forming a pocket between the turned back portion and a portion of the tube upon the mandrel; means for supplying fluid under pressure to the said pocket; 35 and means for causing a relative movement between the mandrel and the turned back holding means.
4. In combination with a rubber tube stripping machine, a ring adapted to trans- 40 versely encircle a rubber tube mounted upon a mandrel and adapted to grip a turned back end of the tube; means for making a pocket formed by the turned back portion substantially air tight, and means whereby a fluid 45 under pressure may be supplied through the ring to the pocket.
5. A process of stripping rubber tubes from circular mandrels consisting of turn- ing back an end of the rubber tube upon 50 itself, gripping the turned back portion and forming a substantially air tight joint between the turned back portion and the tube upon the mandrel; introducing a fluid under pressure into the pocket formed by 55 the turned back portion and at the same time causing a relative movement between the mandrel and the tube gripping means.
6. A process of stripping rubber tubes from mandrels consisting of turning back a portion of the rubber tube upon itself, gripping the turned back portion as well as forming a substantially air tight joint be- 60 tween the turned back portion and that part of the tube on the mandrel; introducing a fluid under pressure to the pocket formed by 65 the turned back portion and causing relative movement between the mandrel and the tube gripping means.
7. An air-ring constructed to pass over a rubber tube mounted upon a mandrel, the 70 outside surface of the air ring being beveled and adapted to receive a turned back portion of the tube; a ring beveled upon the inside, adapted to fit over the beveled out- side portion of the air-ring and over the 75 turned back tube portion to hold the tube tightly in place on the outside of the air- ring; at least one port in the air-ring through which air may be supplied from an outside source to that portion of the air- 80 ring enveloped underneath the turned back tube, and an air sealing ring fixed to the air-ring and having its inside surface fitting snugly against the tube in order to prevent air introduced under pressure through 85 the ports from escaping between the air- ring and the tube mounted on the mandrel.
8. In a tube stripping device, a ring adapted to encircle a mandrel upon which a rubber tube is mounted, means for holding 90 a turned back portion of the tube against the ring, and one or more ports in the ring adapted to introduce a fluid from an outside source to the pocket formed by the turned back tube portion.

CHARLES EDGAR MAYNARD.
